DISPENSING DEVICE FOR PASTE TUBES

William Broaddus Massey, Richmond, Va.

Application July 10, 1944, Serial No. 544,229

9 Claims. (Cl. 222—103)

This invention relates to a device for use in dispensing tooth paste and the like from metal or other collapsible tubes, and particularly to a device which may be used to cause the entire contents of a tooth paste or other tube to be completely and cleanly discharged.

Many devices of various types have been produced for dispensing pastes from collapsible tubes but so far as I am aware none of them has had any substantial use, due, I believe, to the fact that they have been of faulty design, complicated to operate, or too expensive to appeal to the public generally.

In accordance with my invention there is provided a device for use in dispensing paste from tooth paste tubes or the like which may be stamped or otherwise formed from a single piece of metal, plastic, or other material having a suitable degree of resiliency. The device has no complicated parts which makes its use difficult and is sufficiently small and inexpensive to manufacture as to justify its being placed by manufacturers of tooth paste in the cartons in which tubes of such goods usually are packaged for sale to the public.

More particularly my invention provides a pair of pressure plates joined at one end to form a device of generally V-shape which may be slid sidewise over the closed end of a paste tube. When the device has been thus applied to a paste tube and the pressure plates pressed together to apply pressure to opposite sides of the tube the contents thereof progressively are pushed forward towards the discharge opening in the other end of the tube. The end of the device where the pressure plates are joined is provided with a slot through which the flattened portion of the tube from which the contents have been discharged may pass as the device is moved progressively forwardly along the tube.

The pressure plates are so constructed that they grip the tube and prevent the device accidentally falling from the tube after it has once been applied thereto. Thus, once the device has been applied to a tube it will always remain thereon, ready for operation.

At least one, and preferably both of the pressure plates are inwardly convex so that when they are pressed towards one another to apply pressure to the opposite sides of the tube the effect of a rolling action on the tube is obtained, whereby the contents of a tube more effectively are forced forward, cleaning the tube of its contents as the device progressively moves along it.

The invention will be further described in con-

nnection with the accompanying drawing but it is to be understood that such further description and disclosure is by way of exemplification and that the invention is not limited thereto, except to the extent defined in the subjoined claims.

In the drawing,

Fig. 1 is a perspective view of one embodiment of my invention,

Fig. 2 is a side elevational view,

Fig. 3 is a transverse sectional view showing the device in place on a collapsible tube,

Fig. 4 is a view of a blank from which the device shown in Figs. 1-3 is formed,

Fig. 5 is an end view of a modified form of the device embodying my invention,

Fig. 6 is a side elevational view of a still further modification,

Fig. 7 is a transverse sectional view of Fig. 6.

Referring to the drawing, the reference character 1 designates a sheet of metal, plastic or other material having sufficient resiliency to return to a preformed position when deformed therefrom to a limited extent. The sheet 1, shown in blank form in Fig. 4, is bent transversely at its 25 longitudinally center portion to form spaced portions 2 and 3 terminating in jaws 4 and 5 and pressure plates 6 and 7 curving outwardly from the respective jaws 4 and 5. The spaced portions 2 and 3 form a trough for receiving the clamp 30 which closes one end of a collapsible paste tube, as will be more fully described. The blank when bent to its final form is generally of V-shape, when viewed from its edge, as readily may be seen from Fig. 3.

Each of the pressure plates 6 and 7 are slit along longitudinal lines 8 and 9 and transverse lines 10 to form tongues 11 and 12 which extend toward the trough formed by the spaced portions 2 and 3. The tongues 11 and 12 are deformed 35 40 inwardly from the plane of the pressure plates 6 and 7 so that the free ends thereof form abutments 14 for a purpose to be explained.

The bottom of the trough between the spaced portions 2 and 3 is provided with a slot 15 through 45 which the collapsed tube may pass as the device progressively is moved forwardly along the tube.

When the device shown in Figs. 1-3 is to be used it is slid sidewise onto the closed end of a collapsible paste tube 16 so that the trough formed 50 by the spaced portions 2 and 3 receives the clamp 17 at the end of the tube. The jaws 4 and 5 normally lie sufficiently close to one another to engage the collapsed walls at the end of the tube 16 when the device is in place on the tube, as shown in Fig. 3. To facilitate placing the device

on the end of the tube the pressure plates may be slightly sprung apart until the device is in place on the tube.

When the device is in place on a paste tube the end of the tube lies opposite the slot 15 at the base of the trough formed by the spaced portions 2 and 3 and the free ends of the tongues 11 and 12 form abutments which engage the collapsed walls of the tube behind the clamp 17 and thus prevent removal of the tube forwardly between the pressure plates 6 and 7.

When it is desired to dispense paste from the free end of the tube the device is grasped with the tongues 11 and 12 between one's thumb and forefinger and the tongues pressed towards one another to apply pressure to opposite sides of the tube. The pressure applied by the pressure plates collapses the tube and causes a portion of the paste therein to be propelled towards the opening at the opposite end of the tube and the discharge of an amount of the paste from the open end thereof.

Due to the general V-shape of the device, and to the fact that the pressure plates 6 and 7 and the tongues 11 and 12 thereof are inwardly convex, the tongues, when pressure is applied to them, first bear against the lowermost portion of the tube containing the paste and progressively cause pressure to be applied longitudinally of the tube towards the discharge end. Thus there is obtained the effect of a rolling action from the bottom of the portion of the tube containing the paste towards the discharge opening so that the paste in the tube always is progressively moved forwardly and there is no danger of a portion of the paste in the tube being pushed backwardly into a collapsed portion of the tube.

As the device is used to facilitate discharge of the paste from the open end of the tube, the walls of the tube progressively are collapsed and flattened and pass through the slot 15 as shown in dotted lines in Fig. 3.

Owing to the fact that the pressure plates 6 and 7 normally tend to yield or spring from the portion where they are joined to one another, that is, from the bottom portion of the trough opposite the ends of the slot 15, and to the fact that the tongues 11 and 12 normally tend to yield from a line joining the outer ends of the longitudinally extending slits 8 and 9, pressure applied to the tongues 11 and 12 to force them against the side walls of a collapsible tube results in a compound movement of the tongues, with a certain amount of the movement being caused by the pressure plates 6 and 7 yielding along their line of juncture and the tongues 11 and 12 separately yielding along lines joining the outer ends of the slits 8 and 9. Thus, a double action is obtained so far as the tongues 11 and 12 are concerned.

While I find it preferable to make both of the pressure plates 6 and 7 inwardly convex in order to obtain the rolling action above referred to, in some instances it may be desirable to make only one of the pressure plates 6 inwardly convex, while making the other pressure plate 7' planar, as shown in Fig. 5. In such a construction when the tongues 11 and 12' are pressed against opposite sides of a collapsible paste tube the inwardly convex tongue 11 of the pressure plates 6 and 7 will first engage the rearmost portion of the tube containing the paste and progressively bear against the more forward portions of the tube to obtain a rolling action similar to that obtained when both of the pressure plates and the tongues carried by them are inwardly convex,

as described in connection with the form of the invention shown in Figs. 1-3.

In some instances it may not be necessary to slit the pressure plates to form tongues as shown in Figs. 1-3. In Figs. 6 and 7 there is shown an embodiment of the invention in which the pressure plates 6a and 7a instead of being slit to form free tongues are inwardly depressed along transverse lines 18 to form inwardly extending shoulders adapted to engage behind the clamp on the closed end of a paste tube, similar to the manner in which the free ends of the tongues form abutments to engage behind such clamp. Otherwise, the form of the invention shown in Figs. 6 and 7 is the same as the form shown in Figs. 1-3 and the same reference characters are used to designate similar parts.

From the aforesaid it is apparent that the present invention provides a device which effectively may be used to completely and cleanly discharge the paste from a collapsible tube. Also, the device is inexpensive to manufacture and includes no complicated parts which might make it difficult or inconvenient to operate. The device is of such simple construction and so inexpensive to manufacture as to warrant its being placed by manufacturers of tooth paste, without additional charge, in the cartons in which tooth paste ordinarily is sold.

30 I claim:

1. A dispensing device for collapsible tubes or the like comprising a pair of pressure plates connected together along one edge and diverging from a point adjacent where they are connected 35 together, said pressure plates being resilient and adapted to be pressed against opposite sides of a collapsible tube placed between them to discharge paste therefrom, said device having a slot adjacent where the pressure plates are connected 40 together to permit passage of a collapsed portion of a tube from which paste has been discharged, the pressure plates being spaced from one another adjacent their line of juncture a distance sufficient to initially receive the clamp at the 45 closed end of a paste tube, the pressure plates having shoulders just outwardly of the place where they are spaced to receive such clamp normally sufficiently close to one another, when the 50 device initially is placed over the closed end of a tube, to lie forwardly of the edges of such clamp and in alignment with them to function as abutments to prevent removal of the tube forwardly between the pressure plates.

2. A dispensing device for collapsible tubes or the like comprising a pair of pressure plates connected together along one edge and diverging from a point adjacent where they are connected together, said pressure plates being resilient and adapted to be pressed against opposite sides of a 55 collapsible tube placed between them to discharge paste therefrom, said device having a slot adjacent where the pressure plates are connected together to permit passage of a collapsed portion of a tube from which paste has been discharged, the pressure plates being spaced from one another adjacent their line of juncture a distance sufficient to initially receive the clamp at the 60 closed end of a collapsible tube, the pressure plates being slotted to form tongues extending toward their line of juncture, said tongues having their free ends sufficiently close to one another to engage opposite sides of a tube when the 65 sides thereof are collapsed against one another, said free edges of the tongues forming abutments forwardly of the edges of such clamp and in 70 75

alignment with them to prevent removal of the tube forwardly between the pressure plates.

3. A dispensing device for collapsible paste tubes made from a single piece of resilient material bent to form a pair of pressure plates which diverge from one another adjacent their line of juncture, said pressure plates being adapted to be pressed against opposite sides of a collapsible tube placed between them to discharge paste therefrom, said device having a slot adjacent the line of juncture of the pressure plates to permit passage of a collapsed portion of a tube from which paste has been discharged, the pressure plates being spaced from one another adjacent their line of juncture a distance sufficient to initially receive the clamp at the closed end of a paste tube, at least one of the pressure plates having a shoulder adjacent the place where they are spaced to receive such clamp, the distance between the inner edge of such shoulder and the portion of the other pressure plate opposite it being such that they will bear against the walls of such a tube placed between them, when the walls are collapsed against one another, whereby such shoulder lies forwardly of one edge of such clamp and in alignment therewith to form an abutment to prevent removal of the tube forwardly between the pressure plates.

4. A dispensing device for collapsible paste tubes made from a single piece of resilient material bent to form a pair of pressure plates which diverge from one another adjacent their line of juncture, said pressure plates being adapted to be pressed against opposite sides of a collapsible tube placed between them to discharge paste therefrom, said device having a slot adjacent the line of juncture of the pressure plates to permit passage of a collapsed portion of a tube from which paste has been discharged, the pressure plates being spaced from one another adjacent their line of juncture a distance sufficient to receive the clamp at the closed end of a paste tube, each of the pressure plates having shoulders adjacent the place where they are spaced to receive the clamp at the closed end of a tube, said shoulders forming abutments adapted to lie forwardly of the edges of such clamp and in alignment with them to form abutments to prevent removal of a tube placed between the pressure plates forwardly between them, at least one of the pressure plates being inwardly convex so that when the pressure plates are flexed by being pressed against a tube between them to discharge paste from the tube the effective force of such pressure is exerted progressively from the rear forwardly along the tube, whereby the effect of a rolling action on the tube will be obtained.

5. A dispensing device for collapsible paste tubes made from a single piece of resilient material bent to form a pair of pressure plates which diverge from one another adjacent their line of juncture, said pressure plates being adapted to be pressed against opposite sides of a collapsible tube placed between them to discharge paste therefrom, said device having a slot adjacent the line of juncture of the pressure plates to permit passage of a collapsed portion of a tube from which paste has been discharged, the pressure plates being spaced from one another adjacent their line of juncture a distance sufficient to initially receive the clamp at the closed end of a paste tube, the pressure plates being slotted to form tongues extending toward the line of juncture of the pressure plates, said tongues being deformed from the planes of the pressure plates

and having their free ends sufficiently close to one another to engage opposite sides of a collapsible tube when the sides thereof are collapsed against one another to form abutments forwardly of the edges of such clamp and in alignment with them to prevent removal of the tube forwardly between the pressure plates, said tongues being of a width at least sufficient to extend across the major portion of a paste tube inserted between the plates.

10 6. A dispensing device for collapsible paste tubes made from a single piece of resilient material bent to form a pair of pressure plates which diverge from one another adjacent their line of juncture, said pressure plates being adapted to be pressed against opposite sides of a collapsible tube placed between them to discharge paste therefrom, said device having a slot adjacent the line of juncture of the pressure plates to permit passage of a collapsed portion of a tube from which paste has been discharged, the pressure plates being spaced from one another adjacent their line of juncture a distance sufficient to initially receive the clamp at the closed end of a paste tube, at least one of the pressure plates having an inwardly depressed portion forming a shoulder adjacent the place where the pressure plates are spaced to receive such clamp, said shoulder normally being sufficiently close to the portion of the other pressure plate opposite it to lie in alignment with the edge of such clamp and form an abutment to prevent removal of a tube forwardly between the plates.

30 7. A dispensing device for collapsible paste tubes of a single piece of resilient material bent to form a pair of pressure plates which diverge from one another adjacent their line of juncture, said pressure plates being adapted to be pressed against opposite sides of a collapsible tube placed between them to discharge paste therefrom, said device having a slot adjacent the line of juncture of the pressure plates to permit passage of a collapsed portion of a tube from which paste has been discharged, the pressure plates being spaced from one another adjacent their line of juncture a distance sufficient to initially receive the clamp at the closed end of a paste tube, one of said pressure plates being planar, and the other of the pressure plates being inwardly convex so that when it is flexed by being pressed against a tube between the pressure plates to discharge paste from the tube the effective force of such pressure is exerted progressively from the rear forwardly along the tube, whereby the effect of a rolling action on the tube will be obtained.

40 8. A dispensing device for collapsible tubes or the like of a single piece of resilient material folded to form a pair of resilient pressure plates connected together along one edge and diverging from a point adjacent where they are connected together, said pressure plates being adapted to be pressed against opposite sides of a collapsible tube placed between them to discharge paste therefrom, said device having a slot adjacent the fold thereof of such dimensions as to permit passage of a collapsed portion of a tube from which paste has been discharged, at least one of the pressure plates being inwardly convex so that when said inwardly convex plate is flexed by being pressed against a tube between the plates to discharge paste from the tube the effective force of such pressure is exerted progressively from the rear forwardly along the tube, whereby the effect of a rolling action on the tube is obtained.

70 9. A dispensing device for collapsible tubes or

the like comprising a pair of pressure plates connected together along one edge and diverging from a point adjacent where they are connected together, said pressure plates being resilient and adapted to be pressed against opposite sides of a collapsible tube placed between them to discharge paste therefrom, the pressure plates being spaced from one another adjacent where they are connected together to form a trough of sufficient width initially to receive the clamp at the closed 10

end of a paste tube, and being sufficiently close to one another just forwardly of such trough as normally to engage opposite sides of a tube when the sides thereof are collapsed against one another, said trough having a slot extending longitudinally thereof and of such dimensions as to permit passage of a collapsed portion of a tube from which paste has been discharged.

WILLIAM BROADDUS MASSEY.
